Patented Nov. 2, 1926.

UNITED STATES PATENT OFFICE.

MANUEL D. DOMINGUEZ, OF NEW ORLEANS, LOUISIANA, ASSIGNOR TO CHARLES A. DENIS AND GEORGE SARPY, BOTH OF NEW ORLEANS, LOUISIANA.

ELECTRIC HEATER.

Application filed November 22, 1923, Serial No. 676,414. Renewed April 6, 1926.

The invention relates to electric heaters and has as an object the provision of a simple and compact device of the character described which will act automatically to apply heat to the water when the water tap is opened to draw water. A further object of the invention is the provision of a heater having the heated portion of the water pipe insulated in such a manner as to make the electric element readily accessible without disturbing the water connections. A further object of the invention is the provision of a water heater that requires no support other than the water pipe. A further object is the provision of a heater having means for removal of water of condensation. Other objects will appear from the following description when read in connection with the accompanying drawing, wherein,

Figure 1 is a side elevation showing a portion of the heat insulating jacket removed and a portion thereof in section.

Figure 2 is a plan view partly broken away.

Figure 3 is an elevation seen from the left of Fig. 1.

The entire device as shown is adapted to receive its support from the water pipe 10. Water is drawn from the pipe 10 by means of pipe 11 and after passing through the heating coil 12 returns to the pipe 10 by means of the pipe 13 for use. When the heater is to be utilized the valve 14 is closed and the valve 15 is opened. If it be desired to draw water from the tap supplied by the pipe 10 without the use of the heater the valve 15 may be closed and the valve 14 opened, in which case the heater could be removed if desired.

The heating coils 12 are preferably made of a material which is a ready conductor of heat, such as copper, and may be secured to pipes 10 and 13 as by means of unions 16, 17. To heat insulate the coil 12 there is shown an asbestos jacket 18 of substantial thickness, which is preferably formed as two halves of a cylinder, which halves may be secured together by means of wires 19 seated in channels 20 in the surface of the asbestos. To protect the exterior of the insulation a casing 21 is shown preferably formed of aluminum castings of semi-cylindrical form, provided with flanges 22, 55 screwed or bolted together by fastenings

passing through openings 23. The ends of the coil are shown as protected by plugs 24, 25 which are retained by covers 26, 27, secured to the casing 21 by screws.

In the event that cold water is allowed to flow through the coils while the current is cut off from the device, as for instance when the power house is shut down, water may be condensed on the exterior of the coils from the atmosphere. To catch the drain of such water of condensation the plug 25 is shown as formed with a recess lined by means of a metallic bowl 28, provided with an opening at its center, having a tube 29 leading therefrom to the exterior of the device, through an opening in the plug 25, and also through an opening in the cover 27.

An electric heating element is shown diagrammatically at 30, and is preferably of the form shown in my co-pending application Serial Number 676,415, filed November 22, 1923.

The terminals 31 of the element are shown as passed through a suitable opening in the plug 24 and secured to and insulated from the cover 26 by suitable lock nuts and insulating washers. A terminal housing 32 is carried by the cover 26 and may have its side walls cast integral therewith, a cover plate 33 being removably secured at its upper portion by means of screws 34. When so formed, openings in one of the side walls of the casing 32 are provided for passage of the electric conductors 35, 36, the openings being provided with suitable insulating bushings 37. The conductors are shown as secured to the terminals 31 within the casing and as passing to the switch housing 38 containing a pressure-operated switch of the nature disclosed in my co-pending application above referred to.

The pressure-operated switch is shown as supported upon rods 39, 40 mounted upon the valve casing 41 of the switch operating valve.

The device will be seen to be exceedingly compact and neat in appearance, and requires no further support than that of the water pipe itself. The heating element being housed within the coils of the water pipe. The resistance elements of the heater are brought in close proximity to the coils and the heating element and coils are both enclosed in the insulation, so as to provide the most efficient application of the electric

current possible for heating of the water. When the water is flowing through the pipe its rotary motion ensures that all portions of the stream will become heated, so that 5 a uniformly heated stream of water may be drawn from the hot water faucet.

Minor changes may be made in the physical embodiment of the invention without departing from its spirit.

10 I claim:

1. An electric heater comprising a helically coiled pipe, a cylindrical insulating jacket surrounding said coils, insulating plugs closing the ends of said jacket, a 15 heating element mounted on one of said plugs and enclosed by said coils, a metallic casing enclosing said jacket and a metallic plate covering each of said plugs and secured to said casing.
2. An electric heater comprising water 20 pipe connections, a coil carried by said connections, a heating element enclosed by said

coil, a cylindrical insulating jacket surrounding said coil and supported by said connections, a metallic casing enclosing said 25 jacket and having circular openings in its ends, insulating plugs insertable through said openings and closing the ends of said jacket, a concave metallic plate having a central opening in contact with the inner 30 surface of one of said plugs, said plug having a central opening therein, a plate covering the outer surface of said plug, a sleeve connecting said plates and passing through said opening whereby to provide drainage 35 from the interior of said jacket, said outermost plate secured to said metallic casing, a plug of insulating material closing the remaining end of said jacket, a metallic plate covering said last named plug and attached to said casing, and a housing for 40 electrical terminals carried by said last named plate.

MANUEL D. DOMINGUEZ.
